UNITED STATES PATENT OFFICE

160,756

GLASS WASHING MACHINE

Carl B. Webber, Winston-Salem, N. C.

Application September 13, 1949, Serial No. 4,976

Term of patent 14 years

(Cl. D49—1)

To all whom it may concern:

Be it known that I, Carl B. Webber, a citizen of the United States, residing at Winston-Salem, county of Forsyth, State of North Carolina, have invented a new, original, and ornamental Design for a Glass Washing Machine, of which the following is a specification, reference being had to the accompanying drawings, forming a part thereof.

Figure 1 is a front perspective view of a glass washing machine showing my new design;

Figure 2 is a rear perspective view thereof.

I claim:

The ornamental design for a glass washing machine, substantially as shown.

CARL B. WEBBER.
